CLAIM

The ornamental design for a toy rocket, as shown and described.

DESCRIPTION

FIG. 1 is a first perspective view of a toy rocket showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 1; and,

FIG. 11 is an enlarged view of the selected portion 11 in FIG. 2.

The broken lines shown in the drawings depict portions of the toy rocket that form no part of the claimed design. The dot-dash broken lines illustrate the periphery of the enlarged views of the toy rocket and form no part of the claimed design.
